(57) **CLAIM**

The ornamental design an armoire, as shown and described.

DESCRIPTION

FIG. 1 is a front perspective view of an armoire showing my new design;

FIG. 2 is a front view thereof;

FIG. 3 is a side view, the opposite side being a mirror image thereof; and,

FIG. 4 is an enlarged perspective view of one of the drawer pull areas shown in FIGS. 1 and 2.

The broken lines showing the hardware is for illustrative purposes only and forms no part of the claimed design.

1 Claim, 4 Drawing Sheets

FIG. 1

FIG. 2

FIG. 3
